ERNEST E. PALMER, OF TORONTO, ONTARIO, CANADA, ASSIGNOR TO TORONTO TYPE FOUNDRY COMPANY, LIMITED, OF TORONTO, ONTARIO, CANADA.

SHEET-FEEDING MECHANISM FOR PAPER AND THE LIKE.

1,394,574.

Specification of Letters Patent.

Patented Oct. 25, 1921.

Application filed November 29, 1920. Serial No. 427,096.

To all whom it may concern:

Be it known that I, ERNEST E. PALMER, of the city of Toronto, in the county of York, Province of Ontario, Canada, a subject of the King of Great Britain, have invented 5 certain new and useful Improvements in Sheet-Feeding Mechanism for Paper and the like, of which the following is a specification.

10 This invention relates to sheet feeding mechanism of the well known type in which the individual sheets are feathered out and fed forward from a pile of sheets by combing wheels, adapted to be thrown and held 15 out of action as soon as they have fed a sheet to a certain predetermined position and until such sheet has been removed.

More particularly the invention relates 20 to feeders of the type in which the combing wheels are thrown out of action by means of a reciprocating cut-out rack which is put into operative connection with means for lifting the combing wheels by the lifting of a detector finger by a sheet passing under 25 the same.

In such mechanism it is my object to provide a construction in which the transfer or feed drum which feathers the sheets is controlled to operate only while the combing 30 wheels are operative, to provide improved means for throwing the combing wheels out of action, and to provide simple and effective dabber mechanism to hold the remaining sheets while the combing wheels are raised 35 and the first sheet is being drawn away by the mechanism to which sheets are being fed.

I attain my object by means of the constructions hereinafter described and illustrated in the accompanying drawings in which—

Figure 1 is a plan view of part of a sheet feeder provided with my improvements;

Fig. 2 a side elevation of the same;

40 Fig. 3 a vertical section of part of the same showing particularly the combing wheels and means for throwing the same out of action;

Fig. 4 a rear view of the same parts;

50 Fig. 5 a side elevation, partly in section, of part of the operating mechanism for the transfer or feeding rolls;

Fig. 6 a rear elevation of the dabber mechanism;

Fig. 7 a side elevation of the parts shown 55 in Fig. 6; and

Fig. 8 a side elevation showing the relative positions of the dabber operating cam, the crank disk operating the feed roll and cut-out rack, and the cam for lifting the 60 combing wheels.

In the drawings like numerals of reference indicate corresponding parts in the different figures.

1 is part of the transport board of the 65 sheet feeding apparatus provided as usual with feeding tapes 2 operated in any suitable manner. 3 is the transfer or feed roll between which and the curved guides 4 the bank of paper is passed, which paper by the 70 operation of the feed roll is feathered out as shown, this arrangement being old in the art.

The feed roll is operated by the pivoted 75 rock arm 5, which carries a pawl 6 engaging the ratchet wheel 7 fast on a stub shaft 54 driving the spindle of the feed roll 3 by means of the gearing 42. This rock arm has an adjustable bolt and slot connection 8 with one end of a connecting rod 9, the 80 other end of which is connected by an adjustable bolt and slot connection 10 with one end of a lever 11 of the first order fulcrumed on the frame of the machine, and which is operated by a rocking member 12 pivoted on the frame of the machine and engaging the upper end of the lever by a pin and slot connection 13. This rocking member is actuated by means of the pivoted connecting rod 14, the other end of which is connected by 85 a wrist pin with a crank disk 15 on the constantly running shaft 16 of the apparatus. This shaft is actuated in any ordinary manner as will be understood by those conversant with the art.

The rocking member 12, it will be noted, is formed of two arms, one connected with the lever 11 hereinbefore described and the other connected by means of a pin and slot connection 17 with the cut-out rack 18 slidably supported on the frame of the machine. This rack thus has a regular reciprocating movement imparted thereto while the machine is in operation. The particular function of this cut-out rack is to raise the 100 combing wheels at such times as sheets of paper are passing from the feed apparatus to the mechanism to which they are fed. The 105

combing wheels are carried on gear boxes 19 formed as bell crank levers and journaled on the constantly rotating shaft 20, which is driven in any manner known in the art, the 5 combing wheels being driven by a train of gearing 21 from this shaft so that the combing wheels are constantly rotating when the machine is in action.

22 is a bell crank lever fulcrumed on the 10 frame of the machine and engaging the gear box 19 by means of a pin and slot connection 23. By operating the other end of the bell crank lever 22, the combing wheel may be raised and lowered as desired. This lever 15 is operated by the rocking cam 24 journaled on the shaft 16. The outer end of the bell crank lever 22 is preferably provided with a roller 25 for engagement with the cam. Normally the cam is yieldingly retained in 20 the position shown in Fig. 2 by means of a compression spring 26 engaging the cam and a stationary part of the machine, the combing wheel then being in its lower position engaging the topmost sheet of the feathered 25 bank of sheets. By rocking the cam to the position shown in Fig. 3, the combing wheel is raised.

The operating and controlling mechanism for the cam is substantially as follows: 27 30 is a detector finger secured to a shaft 28 journaled in the frame of the machine. To this shaft 28 is secured an arm 30 which normally engages a shoulder 32 formed on the hub of the cut-out pawl 31 pivoted on a 35 downward extension of the cam 24. This detector finger 27, as is common in the art, extends over a grooved pulley 29 over which the paper passes from the transfer board to the mechanism to which it is to be fed. 40 Normally the detector finger drops down into the grooved pulley as shown in Fig. 2. The passage of a sheet of paper, however, raises it to the position shown in Fig. 3. This movement lifts the rock arm 30 secured 45 to the shaft 28 and releases the cut-out pawl 31 and allows its end to drop down by its own weight into engagement with the cut-out rack 18. The result of the pawl being brought into engagement with the cut-out 50 rack is that on the movement of the rack to the left as shown in the drawings, the cam 24 is forced to the position shown in Fig. 3, and the combing wheels thus raised. The instant the rear end of the 55 sheet of paper passes from under the detector finger, the finger is free to drop and releases the rock arm 30 to reengage the shoulder 32 of the pawl 31. Continued movement of the rack to the left brings the 60 shoulder into position for reengagement with the arm, which promptly drops into place. Movement of the rack to the right then disengages it from the pawl and leaves the latter free to lift as the spring 26 returns 65 the cam 24 to the position shown in Figs. 1

and 2. From the above description it will be seen that the lifting of the combing wheels is effected positively and not by the snapping action of the springs, thus avoiding the noise and jar of spring lifts and 70 the trouble and expense of replacing broken springs.

I find it very desirable that the operation of the stepwise movement of the feed roll should occur when the combing wheel is in 75 operation and only at such times. I therefore provide the following mechanism whereby the movement of the combing wheel operating mechanism controls the operation of the feed roll. On the shaft 33, to which 80 is connected the bell crank lever 22, I secure an arm 34, which, by means of the connecting rods 35 and 36 and the bell crank levers 37 and 38, actuates the slide 39 provided with a slot 40 through which passes the 85 spindle of the ratchet wheel 7. The upper end of the slide is provided with a curved surface 41 adapted to engage the pawl to raise it out of engagement with the ratchet wheel, the pawl at such times sliding idly 90 backward and forward on the curved surface 41. It will thus be seen that the raising of the combing wheel also throws the feed roll out of gear.

I find it desirable when the top sheet of 95 the feathered bank of sheets is being drawn away by the mechanism to which the sheet is being fed that the next sheet should be temporarily held to prevent it being drawn forward with the top sheet. I therefore 100 provide a dabber 43 which operates between the combing wheel and the feed roll. This dabber is brought into operation at or about the moment that the feeding movement of the transfer roll ceases. The dabber is actuated by a cam 44 fast on the constantly 105 rotating shaft 16. This cam engages the forward end of a rocking lever 45 fulcrumed on a suitable stationary part. The end of the rocking lever 45, which is engaged by 110 the cam, is preferably provided with an anti-friction roller 46. The dabber 43 has an adjustable swinging movement on the end of an arm 47, a set screw 48 being provided whereby it may be clamped as set. The arm 115 47 is secured to a shaft 49 suitably journaled longitudinally of the apparatus, to which is secured a disk 50 having its periphery notched to form a shoulder 51 engaged by a finger 52 extending laterally from the rear 120 end of the lever 45. A coil spring 53 is secured to the rocking lever 45 and to a suitable stationary part and tends to maintain the roller 46 in contact with the cam 44. By the operation of the cam 44 it is evident that 125 the dabber will be vertically moved as desired.

In general, the operation of the apparatus is as in other sheet feeders of the same general type, a bank of sheets being feathered 130

out and combed away one by one, the combing and the operation of the feed roll, however, being automatically stopped, in my apparatus, at such times as a sheet is passing under the detector finger.

What I claim as my invention is:

1. In sheet feeding mechanism, the combination of a cut-out rack; an oscillatable cam; a cut-out pawl pivoted on said cam adapted to engage the rack; means normally holding said pawl out of engagement with the rack; a pivoted detector finger operable by the passage of a sheet of paper and adapted to cause the engagement of the pawl with the rack; a vertically movable combing wheel; means operable by said cam for moving the combing wheel to its inoperative position; and yielding means tending to return the cam to its normal position.
2. In sheet feeding mechanism, the combination of a reciprocating cut-out rack; an oscillatable cam; a cut-out pawl pivoted on said cam tending to engage the rack and having a shoulder on its hub; a detector shaft; a detector finger secured thereto; an arm on the detector shaft adapted when the detector finger is lowered to engage the aforesaid shoulder to hold the pawl out of engagement with the rack; a vertically movable combing wheel; means operable by said cam for moving the combing wheel to its inoperative position; and yielding means tending to return the cam to its normal position.
3. In sheet feeding mechanism, the combination of a feed drum adapted to feather the sheets; means for imparting a stepwise movement of rotation to the drum including a ratchet wheel and a rock arm carrying a pivoted pawl; a combing wheel; a detector finger; means conditioned for operation by the lifting of the detector finger for raising the combing wheel; and means for lifting the pawl to cause cessation of the movement of the feed drum while the combing wheel is raised.
4. Sheet-feeding mechanism constructed as set forth in claim 3 provided with a dabber adapted to engage the feathered sheets; and means for briefly engaging the dabber with the sheets at or about the time the combing wheel is raised.

5. In sheet feeding mechanism, the combination of a feed drum; a ratchet wheel adapted to rotate the drum; a pivoted rock arm; a pawl carried by the rock arm engaging the ratchet wheel; means for regularly oscillating the rock arm; means for holding the pawl out of engagement with the ratchet

wheel while the rock arm is oscillating; a vertically movable combing wheel; a pivoted detector finger operable by the passage of a sheet of paper; means conditioned for operation by the lifting of the detector finger for raising the combing wheel; and means operable by the operation of the combing wheel lifting means for actuating the aforesaid pawl lifting means whenever the combing wheel is lifted.

6. In sheet feeding mechanism, the combination of a feed drum; a ratchet wheel adapted to rotate the drum; a pivoted rock arm; a pawl carried by the rock arm engaging the ratchet wheel; a lever of the first order fulcrumed on the frame; a connecting rod pivotally connected to the rock arm and to one end of the lever; a rack bar slidable on the frame; a rocking member adapted to actuate the rack bar and the lever; a constantly rotating shaft; means for converting the rotary movement of said shaft into a rocking movement of the rocking member; a vertically movable combing wheel; means normally inoperative actuatable by the rack bar for raising the combing wheel; a detector finger adapted to condition said means for operation.

7. Sheet feeding mechanism constructed as set forth in claim 6 provided with means operable to hold the pawl out of engagement with the ratchet wheel while the rock arm is oscillating; and means operable by the combing wheel raising means, when raising said wheel, for causing the operation of the pawl raising means.

8. Sheet feeding means constructed as set forth in claim 6 provided with a vertically movable dabber adapted to engage the sheets between the feed drum and combing wheel; and a cam on the constantly rotating shaft adapted to actuate the dabber at or about the time the combing wheel is raised.

9. In sheet feeding means, the combination with a feed drum and combing wheel of a dabber adapted to engage the sheets between the feed drum and combing wheel; a rock arm carrying the dabber; a shaft longitudinal of the machine to which the rock arm is connected; a rocking lever parallel with the shaft; means whereby the rocking of the lever rocks the shaft; a constantly rotating shaft; and a cam on said shaft engaging the lever.

Signed at Toronto, Can., this 17th day of November, 1920.

ERNEST E. PALMER.
